UNITED STATES PATENT OFFICE.

MAX ABRAHAMS, OF NEW YORK, N. Y.

ACOUSTIC HORN.

Application filed September 13, 1926. Serial No. 135,214.

My invention relates broadly to acoustic horns and more particularly to a construction of an acoustic horn having a relatively long air column for the efficient reproduction of the entire range of musical notes encountered in radio broadcast reproduction.

One of the objects of my invention is to provide a construction of spirally shaped acoustic horn having a relatively long air column on which a sound generator is arranged to operate for the reproduction of musical notes over a broad range of tone frequencies.

Another object of my invention is to provide a construction of spirally shaped acoustic horn capable of being moulded in spiral formation for providing a rigid spirally shaped air column, the material of the acoustic horn being so formed as to have minimum tendency to vibrate or otherwise undesirably modify the sound being amplified.

Another object of my invention is to provide a flexible skeleton frame construction which may be formed into the shape of a spiral for reproducing the over all physical dimensions of a relatively long air column and upon which material may be deposited and hardened for forming a rigid spirally shaped air column.

Another object of my invention resides in the construction of a spirally shaped acoustic horn formed by winding a flexible reed upon a conical shaped mandrel and wrapping the reed body thus formed with flexible material which is secured in position thereover and subsequently covered with additional layers of material which may be impregnated with a hardener and the mould wound into the shape desired and baked to harden in the final shape.

My invention will be more clearly understood from the specification hereinafter following by reference to the accompanying drawings in which:

Figure 1 represents a mandrel on which the flexible skeleton frame of my invention is formed; Fig. 2 shows a reed partially wound upon the mandrel; Fig. 3 illustrates a layer of cloth partially wound over the reed with a cord or thread wound between the turns of the reed and over the layer of cloth; Fig. 4 illustrates the flexible acoustic horn construction after it is removed from the mandrel and before it is wound into shape prior to the attachment of the bell at

the enlarged end of the horn; Fig. 5 is an enlarged side elevational view partially broken away and in cross-section illustrating the construction of the flexible skeleton frame; Fig. 6 is a cross-sectional view through the horn construction on line 6-6 of Fig. 5; and Fig. 7 is side view partially broken away of one of the embodiments of the spirally shaped acoustic horn of my invention.

The desirability of a long air column for the reproduction of musical notes over a wide range of frequencies has heretofore been recognized but there has been no practical way in which a long air column could be secured in an acoustic horn within small physical dimensions. The manufacture of a horn of long air column has heretofore been so difficult as to render the expense prohibitive for the practical manufacture of acoustic horns of spiral formation on a quantity production basis.

By my present invention I have devised a method of manufacturing an acoustic horn of any desired length which may be formed into a relatively small physical dimension for securing all of the advantageous characteristics of a long air column in the reproduction of sound over a wide range of tone frequencies.

Referring to the drawings in more detail, reference character 1 represents a mandrel substantially in the shape of a truncated cone on which the horn of my invention is formed. In Fig. 2 I have illustrated the construction of the horn of my invention wherein a flexible reed or wire 2 is wound upon the mandrel 1. At the end of the mandrel where the diameter is relatively small I wind the turns of the reed close together between the sound generator and the horn as represented at 3 forming a connection in the nature of a rigid ferrule. Throughout the remainder of the length of the horn the reed 2 has its turns wound in spaced relationship as represented at 4 up to the end 5 where the turns are wound closely together. The closely adjacent turns at 3 and 5 are secured in position by means of tape, glue or other forms of gummed strips. Over the flexible reed skeleton form thus constructed I wind a strip of cloth 6 in spiral formation throughout the length of the reed form, and over this strip of cloth is wound a cord or thread between the spaced turns 4 of the reed 2 in such manner that the cloth 6 is

tightly stretched over the reed form of each of the turns of the skeleton body. The air column thus formed consists of a long, flexible cloth covered conical shaped horn having the appearance of a plurality of sections of gradually increasing diameters from a relatively small diameter to a relatively large diameter. The cloth 6 is tightly stretched over each of the turns of the reed so that the appearance of the flexible horn from the side thereof is that of a long series of semi-circular sections placed side by side throughout the length of the air column. The flexible form as it is removed from the mandrel is shown in Fig. 4 ready for the process of bending into the final shape and the securing of the bell 8 to the end thereof. Over the flexible form I wind strips of cloth 9 which are impregnated with a hardener and the horn body then wound into the shape desired as represented more clearly in Fig. 7. A finishing coating is placed upon the fabric 9 as represented at 10 for ornamenting the surface of the horn and securing a smooth finish throughout the length of the air column. The horn may then be baked or dried for the purpose of hardening the horn in the final shape in which it has been placed. The bell of the horn may be suitably finished and the entire body both inside and outside suitably decorated. The particular form in which the horn in its flexible condition is wound may vary. The spiral formation I have illustrated in Fig. 7 is only one of its possible embodiments for I have also formed the horn by coiling the flexible form in such manner that the ends of the horn are closely adjacent and the intermediate portion of the horn is wrapped upon itself. A variety of shapes may be imparted to the horn for obtaining the long air column within a small physical space. In this way a relatively small cabinet structure may be employed for housing the acoustic horn.

Where desirable the flexible reed may be removed after the horn is hardened or it may remain in the horn for the purpose of adding mechanical rigidity. By a process of dipping the interior walls of the horn may be made smooth and the turns of the reed or thread so rigidly anchored by the construction I have described that there is a minimum tendency for vibratory action of the walls of the acoustic horn and therefore substantially no interference with the amplification of sound emanating from the sound generator which is secured to the end 3 of the acoustic horn for delivery of the amplified sound at the bell 8.

The skeleton frame is made of prime round reed which is the core of the rattan. The material which covers the skeleton frame

may be impregnated and hardened in accordance with the principles set forth in my Letters Patent No. 1,501,032 on acoustic horns, dated July 15, 1924.

While I have described my invention in one of its preferred embodiments I desire that it be understood that modifications may be made and that no limitations upon the invention are intended other than are imposed by the scope of the appended claims.

What I claim as new and desire to secure by Letters Patent of the United States is as follows:

1. An acoustic horn comprising a flexible skeleton frame, a cloth covering said flexible skeleton frame, and an impregnated fabric covering for said first mentioned covering, said skeleton frame being capable of being coiled into the shape of a spiral.

2. An acoustic horn comprising a flexible skeleton frame formed by a member having its turns closely positioned at its extreme ends and more widely spaced intermediate the ends, a wrapping of cloth for said skeleton frame, a thread wound over said cloth and between the turns of said skeleton frame intermediate the ends thereof for stretching said cloth over said mould, and an impregnated covering for said cloth whereby said skeleton frame may be coiled into compact space while obtaining an air column of relatively long length.

3. An acoustic horn comprising a flexible reed wound into a plurality of successive convolutions; each of said convolutions gradually varying in diameter from a relatively small diameter at one end to a relatively large diameter at the other end, a strip of material spirally wound over said flexible reed and rigidly secured with respect to the convolutions thereof, the acoustic horn thus formed being coiled into spiral formation and a hardening coating for said horn for rigidly securing said horn in the form in which it is coiled.

4. An acoustic horn comprising a flexible reed wound into a plurality of successive convolutions, each of said convolutions gradually varying in diameter from a relatively small diameter at one end to a relatively large diameter at the other end, a strip of material spirally wound over said flexible reed, a cord wound over said strip of material and between the convolutions of said flexible reed for stretching said material over each of the convolutions of said flexible reed, an impregnated covering for said material, said acoustic horn being capable of being coiled into spiral formation, and a baked covering for said horn.

In testimony whereof I affix my signature.

MAX ABRAHAMS.
